DOMESTIC APPLIANCE

Donald K. Ferris, Dayton, Ohio, assignor to General Motors Corporation, Dayton, Ohio, a corporation of Delaware

Application June 30, 1939, Serial No. 282,228

29 Claims. (Cl. 38—54)

This invention relates to domestic appliance, and more particularly to ironing machines.

An object of this invention is to provide an improved ironer with a small shoe by which wearing apparel may be readily ironed, the small shoe being coordinated with the other shoe to form a large shoe structure for efficient ironing of flat work.

Another object of this invention is to provide an ironing machine which is easily changeable from an adjustment for ironing wearing apparel, to an adjustment for ironing flat work without the necessity of shifting the shoe structure.

Further objects and advantages of the present invention will be apparent from the following description, reference being had to the accompanying drawings, wherein a preferred form of the present invention is clearly shown.

In the drawings:

Fig. 1 is a view in perspective of my improved ironer in idle position;

Fig. 2 is a view similar to Fig. 1, but showing the ironer with the small shoe in position for ironing odd shaped articles;

Fig. 3 is an elevation, partly in cross-section, of the shoe side of the ironer;

Fig. 4 is a top elevation of the outer end of the roller shoe construction, and showing the small shoe attachment for use in ironing odd shaped articles;

Fig. 5 is a view, somewhat diagrammatic, showing the heating mechanism internally placed in the small shoe;

Fig. 6 is a cross-sectional view, with parts omitted, indicating the position of the roller and shoe structure with the shoe structure at its maximum retraction;

Fig. 7 is a view similar to Fig. 6, but showing the shoe structure brought into engagement with the roller;

Fig. 8 is a view similar to Fig. 7, but showing certain portions in cross-section;

Fig. 9 is a view similar to Fig. 6, but showing the major shoe at its maximum retraction and the small shoe at intermediate retraction, in readiness to bring the small shoe into engagement with the roller while lifting the major shoe out of engagement;

Fig. 10 is a view similar to Fig. 9, but showing the small shoe in engagement with the roller and the major shoe slightly retracted to allow the ironing of odd shaped articles;

Fig. 11 is a diagrammatic showing of the controls for the heating elements of the two shoes.

Fig. 12 is a fragmentary view illustrating the shape of the small shoe; and

Fig. 13 is a vertical cross-sectional view through the gear box 21.

5 An ironing machine embodying my invention includes a stand 10, a roller or padded member 11, a major shoe 12 and a small shoe 13. The arrangement is such that, by actuating certain controls, it is possible to bring the small shoe 13 alone into engagement with the roller 11, and to cause the roller or padded member 11 either to rotate or remain stationary as desired. By changing the controls, it is also possible to bring both the major shoe 12 and small shoe 13 both 10 into engagement with the roller, with or without the rotation of the roller. By another change in the controls, it is possible to bring the major shoe 12 alone into engagement with the roller and to have the roller rotate or remain stationary. If 15 desired the drive mechanism for the roller may be of the variable speed type with an adjustment to obtain the selected speed. Any method of placing the shoes in contact with the padded member may be used, either the shoes being moved or the padded member being moved, or both.

20 The small shoe 13 is so coordinated with the major shoe 12 that, when they are brought together against the roller, they form a substantially unitary large shoe for use in ironing flat work, or pressing clothes. On the other hand, the small shoe 13 alone, or the major shoe 12, can be brought against the roller. The small shoe 13 is so shaped that wearing apparel may be readily ironed, and a large number of the operations usually performed only with a hand iron can be easily performed on the ironing machine with the aid of the small shoe 13.

25 The shoes 12 and 13 are divided diagonally or out of parallel with the direction of rotation of the roller to form the diagonal shoe edges 13a and 12a. The edge 13a merges with the curved leading edge 13b to form the point 13c. By this construction the small shoe 13 is given a shape very nearly the same as an ordinary hand iron, and may be readily used for ironing the sleeves, collars, etc., of wearing apparel. On the other hand, the diagonal edges 12a and 13a cooperate when shoes 12 and 13 are used together, to form a 30 larger, unitary shoe structure for ironing flat work and present a substantially curved end which is useful in ironing both wearing apparel and flat work. The seam formed by edges 12a and 13a does not crease the flat work because it 35 is diagonally directed, and thus irons out any

crease that would otherwise tend to form. By this construction the two shoes 12 and 13 present a relatively continuous or smooth front to the on-coming work when used together for use with flat work, and the small shoe 13, when used alone, presents a relatively pointed front for use with wearing apparel. As the article to be ironed passes under the two shoes, when used together, an unbroken path of ironing contact is produced on the article to be ironed, which is wider than the large shoe, and which contains no crease at the place where the two shoes meet. This is due to the overlapping or diagonal contact between the two shoes, which prevents the formation of any crease at this point.

The small shoe 13 may be heated by a heating element 13d, preferably placed along the edge of the shoe. This heating element 13d may be controlled by the opening and closing of thermostatic switch 13e placed in the shoe.

The large shoe 12 is provided with a heating element 12d placed in the shoe and controlled by the thermostatic switch 12e placed in the shoe.

A manual switch S is provided which energizes selectively the small shoe heater 13d, the large shoe heater 12d or both together.

The small shoe preferably is placed adjacent the open end of the roller to facilitate the ironing of wearing apparel.

The controls for operating and adjusting the ironer are so placed that they are easily actuated by the user. For example, the pedal 15, when depressed, initiates a cycle of operations such as to bring the selected shoe, or shoes, into engagement with the roller, and simultaneously to cause the roller to rotate, or to remain stationary, as so desired. The levers 16 and 17 are so arranged that, when they are moved towards the operator, they cause the respective shoes 12 and 13 to be brought into engagement with the roller 11 when the pedal is depressed. If these levers are moved away from the user, they prevent the shoes 12 and 13 from coming into contact with the roller 11 when the pedal 15 is depressed. By bringing forward either of the levers 16 or 17 while permitting the other lever to remain in the back position, the corresponding shoe 12 or 13 respectively alone is brought into contact with the roller 11 when the pedal 15 is depressed. The handle 18 is used to control the roller operation, causing the roller to rotate or to remain stationary, as selected when the pedal is depressed.

The shoe structure is actuated by the horizontal rod 20. This rod is rocked about its axis by any suitable mechanism in the gear box 21, well known in the art. Mechanisms for actuating the rod 20 counterclockwise and the roller 11 clockwise under control of a pedal or handle are well known. Merely as examples, suitable mechanisms are shown in U. S. patent to Janda 2,026,345; Foley 1,970,511; and Peter et al. 1,921,301, which perform one or more of these operations.

The shoes 12 and 13 are mounted on the rod 20 to be brought into engagement with the roller 11 by the counterclockwise rocking movement of the rod 20. To this end, the rod 20 carries cantilever supports for the shoes in the form of leaf springs 22 and 23 inside of lever-like housings 24 and 26. The housings 24 and 26 are freely rotatably mounted on the shaft 20. The shoe 12 is hingedly carried by means of pin 25 on housing 24, which pin also carries the lever control 16. Shoe 12 is loosely mounted on pin 25 so that the

lever 16 can be rotated about the axis pin 25 without affecting the shoe. This shoe 12 rests loosely on the housing 24 when retracted, as shown in Figs. 6, 9 and 10. The lever 16, when pulled forward by the user, has its lower end 16a wedged into engagement with the spring 22, as indicated in Figs. 7 and 8, so that, when the rod 20 is rocked counter-clockwise, the spring 22 forces the shoe 12 into engagement with the roller 11. When in the position shown in Figs. 7 and 8, the shoe 12 does not rest on housing 24. On the other hand, when the lever 16 is pushed away from the user, to swing it about the pin 25 (in a clockwise direction), the end 16a of the lever 16 is moved out of wedging engagement with the spring 22, as indicated in Figs. 6, 9 and 10, so that when rod 20 is rocked forward in a counter-clockwise direction, the shoe 12 does not come into contact with the roller 11 but rests loosely on housing 24. Shoe 13 has a similar construction, and is similarly connected to the rod 20. The lever control 17 causes the shoe 13 to engage the roller 11, when the lever is in its forward position and when the rod 20 is rocked forward. Engagement of the shoe 13 is prevented when the lever is in its back position. To this end, the spring 23, similar to the spring 22, is secured to the rod 20 and is enclosed in a housing 26, similar to the housing 24. The lever 17 swings about a pin 27, similar to the pin 25, so that its lower end 17a can engage the spring 23 in a manner similar to that described with respect to shoe 12. The shoe 13 is loosely mounted on the pin 27, so that the lever 17 may be rocked independently of the shoe. Springs 30 and 31 are provided to cause positive retraction of the corresponding shoe structure (12 or 13) when the rod 20 is rocked in a clockwise direction to disengage the shoes from the roller. Thus, by the setting of the levers 16 and 17, the user can select whether the shoe 12 alone, the shoe 13 alone, or both shoes together, shall engage with the roller 11 when the pedal 15 is depressed. The levers 16 and 17 also act as quick releases should the user desire quickly to release the corresponding shoe from the roller. This is accomplished merely by knocking the levers away from the user while the corresponding shoe is still in engagement with the roller.

Proper driving mechanism is provided to cause the rod 20 to swing the shoe or shoes into engagement with the roller 11, and to cause the roller to rotate or remain stationary. This mechanism is housed in the box 21 and is driven by the motor 40.

This mechanism may be of any well known construction, such as illustrated in Fig. 13, which may be readily understood by reference to Fig. 2 and to the Janda Patent No. 2,026,345 previously referred to. Fig. 13 shows portions of the Janda patent Fig. 2, slightly modified, and applied to applicant's structure. Certain reference numerals from the Janda patent have been repeated, with the letter J affixed in order to identify the same. In Fig. 13 the motor 40 is shown in vertical position connected, by beveled gearing, to the worm shaft 59J.

When the user wishes to operate the ironer, the levers 16 and 17 are placed in proper positions to cause either or both of the shoes 12 and 13 to become operative and the clothes are placed on the roll 11. The pedal 15 is then depressed, and quickly released. This depresses the upper end 121J, of the rod 36, and causes the motor 40 to rotate the eccentric structure 75J 180° to the po-

sition shown in Fig. 13. This causes the arm 78J, and arm 83J, to rock the shaft 20 counterclockwise, and to bring either or both of the shoes 12 and 13 into contact with the roll 11. This movement also rocks the arm 84J, through a lost motion connection 89J, thus lowering the clutch fork member 91J. This actuates the clutch mechanism, further illustrated and described in the said Janda patent, and causes the motor 40 to rotate the bevel pinion 51J, the bevel gear 53J and the roll 11. The ironer then continues to operate with the shoe or shoes 12 and 13 against the rotating roll 11 until the user again depresses the pedal 15, and quickly releases it. This again lowers the upper end 12J of the rod 36 to cause the eccentric structure 75J to rotate 180° from the position shown in Fig. 13. This rocks the shaft 20 clockwise, to move the shoe or shoes 12 and 13 away from the roll 11, and raises the clutch fork member 91J to declutch the bevel pinion 51J, and thus stop rotation of the roll 11.

Should the user wish to stop rotation of the roll 11 while the shoes are in contact therewith, or wish to maintain the roll 11 stationary while causing the shoes to be actuated into contact with the roll, the handle 18, which corresponds to handle 102 of the Janda patent, may be turned to rotate the shaft 97J to another position. This prevents the clutch mechanism 91J from actuating the bevel pinion 51J, as more fully described in the said Janda patent. Thus by moving the handle 18 in one direction, the roll 11 may be caused to rotate when the shoes are in contact therewith, or by moving the handle 18 in the other direction, the roll 11 may be caused to remain stationary when the shoes are in contact therewith.

Further details of construction and operation of this transmission are illustrated and described in the said Janda patent, to which reference is made for a further understanding of its operation.

By this arrangement, the user can easily adjust the ironer for ironing wearing apparel, ironing flat work, or pressing clothes.

The shape of my small shoe is of particular advantage when applied to a roller. By having the edges 13a and 13b directed towards the same oblique point 13c, a special advantage is created when ironing wearing apparel having seams. Ordinarily the user can see only the front part, 13b, 13c of the shoe. If the small shoe were shaped exactly like the ordinary hand iron, with the point at the central axis of the iron, it would be necessary to guide a longitudinal seam for a long distance around the roll until the seam would reach the widest part of the iron. However, since the point of my shoe is the farthest offset point on that side of the shoe, the user can feed the seam of the clothes past the point 13c, and after that it is unnecessary to watch the clothes as they pass to the lower back portion of the roll beyond the "horizon." In order to show this feature more clearly, Fig. 12 has been drawn to illustrate the advantages of this feature. In Fig. 12 the point 13c is shown ironing wearing apparel adjacent to the seam 50 of the wearing apparel. The "horizon" or point where the user's vision around the roll becomes obscured, is indicated by the line 51. It is thus seen that the small shoe 13 has ironed the apparel close to the seam 50 in the visible area of the roll, and it is unnecessary to follow visually the wearing apparel beyond the "horizon" 51. In addition, the shape of an ordinary hand iron has

been indicated by the dotted line 52, in Fig. 12 with the point of the iron at 53 along the central axis of the iron. If it is desired to iron wearing apparel adjacent to the seam 50, it is necessary to feed the seam so that the edge 54 of the iron can iron the apparel adjacent to the seam. However, the seam 50 does not reach the iron edge 54 until the straight edge of the iron is reached at the point 55, which point is quite likely to be beyond the "horizon" 51 because of the curvature of the roll. Thus, by having the small shoe point 13c at a place where it marks the farthest offset point from the central axis of the iron along one edge, an outstanding advantage is obtained.

The control levers 16 and 17 are provided with adjustable ends 16a and 17a which have screw-threaded engagement in the lever blocks 16b and 17b. The adjustable ends 16a and 17a may be adjusted as to length with this threaded engagement, and then secured at the selected adjusted length by means of the lock nuts 16c and 17c. The user may thus adjust the pressure produced on the shoes 12 and 13 by the levers 16 and 17.

While the form of embodiment of the invention as herein disclosed, constitutes a preferred form, it is to be understood that other forms might be adopted, all coming within the scope of the claims which follow.

What is claimed is as follows:

1. An ironer comprising a padded member, a unitary rock shaft adjacent to said padded member, a first support on said rock shaft, a first shoe on said support, a second support on said shaft, a second shoe on said second support, and controls for causing at least one of said shoes to come into working contact, or to remain out of working contact, with said padded member when said rock shaft rocks said supports toward said padded member.

2. An ironer comprising a padded member, rock shaft means adjacent to said padded member, a leaf spring support on said rock shaft means, a first shoe on said leaf spring support, a second support on said rock shaft means, a second shoe on said second support, and a lever control on said leaf spring support for causing said first shoe to come into working contact, or to remain out of working contact, with said padded member when said rock shaft means rocks said leaf spring support toward said padded member.

3. An ironer comprising a padded member, rock shaft means adjacent to said padded member, a first leaf spring support on said rock shaft means, a first shoe on said leaf spring support, a second leaf spring support on said rock shaft means, a second shoe on said second leaf spring support, a lever control on said first leaf spring support for causing said first shoe to come into working contact, or to remain out of working contact, with said padded member when said rock shaft means rocks said first leaf spring support toward said padded member, and another lever control on said second leaf spring support for causing said second shoe to come into working contact, or to remain out of working contact, with said padded member when said rock shaft means rocks said second leaf spring support toward said padded member.

4. An ironer comprising a roller, a rock shaft adjacent to said roller, a first leaf spring support on said rock shaft, a first shoe on said leaf spring support, a second support on said rock shaft, a second shoe on said second support, and a lever control on said first leaf spring support

for causing said first shoe to come into working contact, or to remain out of working contact, with said roller when said rock shaft rocks said first leaf spring support toward said roller.

5. An ironer comprising a movable padded member for carrying an article to be ironed, a large shoe and a small shoe having overlapping edges and cooperating with one another and with the movable padded member to provide an unbroken path of ironing contact wider than said large shoe, means for placing said shoes independently or together in ironing contact and out of ironing contact with said padded member, and a single lever for controlling both shoes simultaneously when used together in forming said main shoe, said small shoe being adjacent an open end of said padded member and being supported to permit insertion of clothing past said open end.

6. An ironer comprising a padded member, a shoe, a rock shaft adjacent to said padded member, a cantilever leaf spring secured to said shaft, a lever-like housing rotatably mounted on said shaft about said spring, a control lever fulcrumed on said housing and having on and off engagement with said spring, said shoe being swingingly secured to said rock shaft by said lever, housing and spring, and being adjustable for working engagement or free clearance by said lever when said rock shaft moves said spring toward said padded member, and adjustable means for regulating the tension of said leaf spring on said shoe.

7. An ironer comprising a roller, a shoe, a rock shaft adjacent to said roller, a cantilever leaf spring secured to said shaft, a lever-like housing rotatably mounted on said shaft about said spring, a control lever fulcrumed on said housing and having on and off engagement with said spring, said shoe being swingingly secured to said rock shaft by said lever, housing and spring, and being adjustable for working engagement or free clearance by said lever when said rock shaft moves said spring toward said roller, a second cantilever leaf spring secured to said shaft, a second lever-like housing rotatably mounted on said shaft about said second spring, a control lever fulcrumed on said second housing and having on and off engagement with said second spring, said second shoe being swingingly secured to said rock shaft by said second lever, second housing and second spring, and being adjustable for working engagement or free clearance by said second lever when said rock shaft moves said second spring toward said roller, one of said shoes being relatively small for ironing wearing apparel independently of the other of said shoes.

8. An ironer comprising a roller, a shoe, a rock shaft adjacent to said roller, a cantilever leaf spring secured to said shaft, a lever-like housing rotatably mounted on said shaft about said spring, a control lever fulcrumed on said housing and having on and off engagement with said spring, said shoe being swingingly secured to said rock shaft by said lever, housing and spring, and being adjustable for working engagement or free clearance by said lever when said rock shaft moves said spring toward said roller, and means for retracting said shoe from said roller.

9. An ironer comprising a roller, a shoe, a rock shaft adjacent to said roller, a cantilever spring member secured to said shaft, a lever-like housing member rotatably mounted on said shaft about said spring, a control lever fulcrumed on one of said members and having an on and off engagement with the other of said members, said

5 shoe being swingingly secured to said rock shaft by said lever, housing and spring, and being adjustable for working engagement or free clearance by said lever when said rock shaft moves said spring towards said roller.

10. An ironer comprising a movable padded member, a large shoe, a small tapered shoe, said shoes having mating adjacent edges and means for placing said small shoe alone or together with said large shoe forming a unitary compound shoe in contact with said padded member, said shoes together presenting a substantially unbroken leading edge, said shoes being relatively fixed longitudinally of the roller.

11. An ironer comprising a padded member, a shoe, a rock shaft adjacent to said padded member, a cantilever spring member secured to said shaft, a lever-like housing member rotatably mounted about said shaft adjacent said spring, a control lever fulcrumed on one of said members and having an on and off engagement with the other of said members, said shoe being swingingly secured to said rock shaft by said lever, housing and spring, and being adjustable for working engagement or free clearance by said lever when said rock shaft moves said spring towards said padded member.

12. An ironer comprising a movable padded member, a large shoe, a small shoe, said shoes having adjacent mating edges, and means for placing said small shoe alone or with said large shoe in contact with said padded member, said small shoe having a leading point extending laterally at least as far as the remainder of the edge of the shoe on that side of the shoe and mating with said large shoe to form a unitary combined shoe with a substantially unbroken leading edge.

13. An ironer comprising a movable padded member for carrying an article to be ironed, a large shoe and a small shoe having overlapping edges and cooperating with one another and with the movable padded member to provide an unbroken path of ironing contact wider than said large shoe, a motor, operating and release means, actuating selectively from said motor, one shoe section or more than one shoe section together into or out of ironing contact with the padded member.

14. An ironer comprising a rotatable padded member for carrying an article to be ironed, a motor, a large shoe and a small shoe having overlapping edges and cooperating with one another and with the rotatable padded member to provide an unbroken path of ironing contact wider than said large shoe, a transmission between said motor and padded member for causing rotation of said padded member, a station clutch for causing contact of said shoes with said padded member, and means for actuating both of said shoes together and either shoe separately with said station clutch.

15. An ironer comprising a rotatable padded member for carrying an article to be ironed, a motor, a large shoe and a small shoe having overlapping edges and cooperating with one another and with the movable padded member to provide an unbroken path of ironing contact wider than said large shoe, said small shoe having a pointed leading edge, a transmission between said motor and padded member for causing rotation of said padded member, a station clutch for causing contact of said shoes with said padded member, and means for actuating both

of said shoes together and either shoe separately with said station clutch.

16. An ironer comprising a substantially cylindrical roll, means for rotating and supporting said roll at one end of the roll, the other end of the roll being free and unsupported, a large shoe and a small shoe cooperatively mounted to produce a relatively long and narrow shoe structure adjacent said roll having a substantially straight leading edge along the major portion of its length, means for moving said structure against said roll with said shoes together as a unit, and for moving said small shoe alone, the end of said structure adjacent the free end of the roll being convexed toward said free and unsupported end of said roll, and merging with said substantially straight leading edge.

17. An ironer comprising a movable padded member for carrying an article to be ironed, a large shoe and a small shoe having overlapping edges and cooperating with one another and with the movable padded member to provide a main shoe producing an unbroken path of ironing contact wider than said large shoe, means for placing said large shoe and said small shoe independently or together in contact and out of contact with said padded member, and a single lever for controlling both shoes simultaneously when used together in providing said main shoe and for controlling either shoe independently of the other.

18. An ironer comprising a movable padded member for carrying an article to be ironed, a large shoe and a small shoe having overlapping edges and cooperating with one another and with the movable padded member to provide an unbroken path of ironing contact wider than said large shoe, means for placing said small shoe alone or together with said large shoe in contact with said padded member, and said shoes being separated by substantially parallel edges disposed at an acute angle to the direction of movement of said padded member to prevent the formation of creases by said edges when said shoes are placed together in contact with said padded member.

19. An ironer comprising a movable padded member, a large shoe and a small shoe adjacent one another and cooperating to provide a main shoe, means for placing said small shoe alone or together with said large shoe in contact with said padded member, said small shoe being provided with a leading edge tapering away from said large shoe and merging with the leading edge of said large shoe and said shoes being separated by substantially parallel edges disposed at an acute angle to the direction of movement of said padded member to prevent the formation of creases by said edges when said shoes are placed together in contact with said padded member, mountings for said shoes arranged so that said shoe edges provide said main shoe with a relatively continuous front to oncoming work and the edge of said small shoe when placed alone in contact with said padded member with a relatively pointed front to oncoming work.

20. An ironer comprising a rotatable cylindrical roller for carrying an article to be ironed, a relatively large arced shoe movable to and away from said roller, a relatively small arced shoe movable to and away from said roller, said shoes having substantially overlapping edges and cooperating with one another and with the cylindrical roller to provide an unbroken path of

ironing contact wider than said large arced shoe, and means for moving said shoes together and said small shoe independently of said large shoe to and away from said roller.

21. An ironer comprising a rotatable cylindrical roller for carrying an article to be ironed, a relatively large arced shoe movable to and away from said roller, a relatively small arced shoe movable to and away from said roller, said shoes having overlapping edges and cooperating with one another and with said cylindrical roller to provide an unbroken path of ironing contact wider than said large arced shoe, power means, means for connecting said power means to said roller, means for connecting said large shoe to said power means for movement of said large shoe to and away from said roller, a controlling manipulator for said last named means, means for connecting said small shoe to said power means for movement of said small shoe to and away from said roller, and a controlling manipulator for said last named means, said manipulators being actuatable to cause movement of said shoes either together or independently of each other.

22. An ironer comprising a rotatable cylindrical roller for carrying an article to be ironed, a relatively large arced shoe movable to and away from said roller, a relatively small arced shoe movable to and away from said roller, said shoes having substantially overlapping edges and cooperating with one another and with the cylindrical roller to provide an unbroken path of ironing contact wider than said large arced shoe, power means, means for connecting said power means to said roller, means for connecting said large shoe to said power means for movement of said large shoe to and away from said roller, a controlling manipulator for said last named means, means for connecting said small shoe to said power means for movement of said small shoe to and away from said roller, and a controlling manipulator for said last named means, said manipulators being actuatable to cause movement of said shoes either together or independently of each other.

23. An ironer comprising a rotatable cylindrical roller, a relatively large arced shoe movable to and away from said roller, a relatively small arced shoe movable to and away from said roller, power means, means for connecting said power means to said roller, means for connecting said large shoe to said power means for movement of said large shoe to and away from said roller, a controlling manipulator for said last named means, means for connecting said small shoe to said power means for movement of said small shoe to and away from said roller, a controlling manipulator for said last named means, said manipulators being actuatable to cause movement of said shoes either together or independently of each other, and a clutch means controlled by a third manipulator for moving said shoes as selected by said two first named manipulators.

24. An ironer comprising a rotatable cylindrical roller, a relatively large arced shoe, a relatively small arced shoe, said shoes having substantially mating adjacent edges to form a unitary compound shoe, a first manipulator for conditioning said large shoe to contact said roller, a second manipulator for conditioning said small shoe to contact said roller, said manipulators being movable into conditioning position independently of each other, power means, trans-

mission means for causing relative movement between said shoes and roller to bring said shoes and roller into contact with each other, and a third manipulator controlling the operation of said transmission means.

25. An ironing machine comprising a large shoe, a small shoe, a padded member movable with respect to said shoes adapted to carry work to the front of and under said shoes, means for placing both of said shoes together or said small shoe alone in contact with said padded member, said shoes presenting a relatively continuous front to said work when used together and said small shoe presenting a relatively pointed front to the oncoming work when used alone.

26. An ironer comprising a rotatable ironing member presenting an ironing surface of predetermined length, means for rotating said rotatable member, a long ironing shoe of substantially shorter length than said predetermined length of said rotatable member, a short ironing shoe, means for moving said short shoe alone or both of said shoes into ironing relation with said rotatable member, and said long shoe and said short shoe cooperating with one another to form aligned complementary portions of a compound shoe member having an ironing surface substantially equal to but not longer than said predetermined length of said rotatable member when both shoes and said rotatable member are brought together in ironing relation.

27. An ironer comprising, a long ironing shoe, a short ironing shoe, a rotatable padded member of predetermined length adapted to carry work to the front of and under said shoes, means for rotating said rotatable padded member, means for moving said short shoe alone or both of said

shoes into ironing relation with said padded member, said shoes cooperating with one another when used together to form aligned complementary portions of a compound shoe member presenting a relatively continuous front to oncoming work and having an ironing surface substantially equal to but not longer than the predetermined length of said padded member, and said shoes having parallel meeting edges disposed at an acute angle to the path of rotation of said padded member to prevent the formation of creases in the work when both shoes are used together.

28. An ironer comprising a movable padded member adapted to carry an article to be ironed, means for moving said member, and a shoe adapted to have ironing contact with said member to produce an ironing path on said article as it is moved past the said shoe, said shoe having a leading point positioned far to one side of the central line of said path and substantially at the extreme laterally outward point of the shoe which produces one lateral edge of said path, said leading point being in advance of any other part of said shoe in the direction of the oncoming article to be ironed.

29. An ironing machine comprising a rotatable roll, a large shoe, a small shoe, said shoes having ironing surfaces alignable substantially into a unitary ironing surface, rockable supports for said shoes in the rear of said roll, individual control levers for said shoes to render said rockable supports effective or ineffective to bring both shoes or one shoe in ironing contact with said roll, and power means to rotate said roll and to rock said rockable supports.
